UNITED STATES PATENT OFFICE.

WALTER J. MC VICKER, OF MINNEAPOLIS, MINNESOTA.

INTERNAL-COMBUSTION ENGINE.

1,146,435.

Specification of Letters Patent. Patented July 13, 1915.

Application filed August 9, 1912. Serial No. 714,211.

To all whom it may concern:

Be it known that I, WALTER J. MC VICKER, a citizen of the United States, residing at Minneapolis, in the county of Hennepin and State of Minnesota, have invented certain new and useful Improvements in Internal-Combustion Engines, of which the following is a specification, reference being had to the accompanying drawings, forming part of this specification.

My invention relates to internal combustion or explosive engines using a liquid hydro-carbon as a fuel, and one principal object in view is the provision of an organization such that fuels of widely different character, such as crude oil, alcohol, kerosene, or gasoline may be used efficiently in the same engine. To this end I have devised novel pumping and injecting mechanism for supplying charges of fuel into the combustion chamber of the engine.

A further feature is the provision of a governing mechanism controlling such fuel pumping and injecting mechanism whereby the speed of the engine is controlled.

With these and other incidental objects and advantages in view my invention consists in certain novel combinations and arrangements of parts, the elements whereof are more particularly pointed out and recited in the appended claims.

In the accompanying drawings I have illustrated my invention as applied to and forming part of a two-stroke-cycle engine.

Of the drawings Figure 1 is a vertical section taken diametrically of the main and supplemental cylinders and also of the crank shaft of the engine; Fig. 2 is a view at right angles to the line of view of Fig. 1; Fig. 3 is a fragmentary section on the same plane as Fig. 1, but with the valves in a different position; Fig. 4 a detail horizontal section on the irregular line 4-4 of Fig. 1, and Fig. 5 a view of parts lying beyond a plane taken on the line 5-5 of Fig. 1, looking in the direction of the arrow.

The same letters of reference are used to indicate the same parts in the several views.

The engine shown in the drawings and with reference to which my invention will be described is of the vertical type, having formed in its base portions 1 a closed crank chamber A provided with an inwardly opening check valve 2, the opposite walls of said crank chamber being formed to provide bearings for the crank shaft 3, which

latter carries the crank 4 within the chamber.

Superimposed upon the base 1 is the main cylinder 5, within which reciprocates the main or working piston 6, connected to the crank 4 by the connecting rod 7, the piston thus separating the chamber A, which constitute an air-compressing chamber, from the combustion chamber B above the piston. Above the upper limit of the stroke of the piston the combustion chamber is much reduced in size at the portion B' of such chamber. The cylinder is provided with a system of communicating water passages C constituting a water jacket to prevent excessive heating. At the top of the cylinder the water jacket communicates through piping 8 with the steam dome 9, and also with a suitable water supply.

An exhaust port and passage D arranged to be uncovered by the piston and place the combustion chamber in communication with the atmosphere near the limit of the downward stroke of the piston is provided, this port being sealed by the piston during the upper part of its travel. An air inlet or intake port E communicating with the compression chamber A is arranged to be uncovered by the piston immediately after it has uncovered the exhaust port D, the port E being also sealed by the piston during the upper part of its travel.

At one side of the portion B' of the combustion chamber is arranged a hot bulb or ignition chamber F surrounded by a housing 10, at the top of which is placed a ventilator 11 having a damper by which the passage of air through the ventilator may be controlled. A torch 12 is arranged adjacent the hot bulb to provide auxiliary means for heating it.

The general construction and arrangement of parts thus far described is common to many engines already known, and my new devices for delivering fuel to the combustion chamber of the engine will now be described. Briefly stated, these parts comprise a fuel pump for delivering small measured charges of fuel, and an auxiliary cylinder and piston for atomizing or vaporizing the same and forcing it into the combustion chamber of the engine at the proper point of its stroke.

The fuel pump comprises a casting in which is formed the passage or chamber G, connected with the fuel tank 13 through the

supply pipe 14, and connected with the vaporizing devices to be hereafter described through the discharge pipe 15. An inwardly opening suction check valve 16 permits the passage of fuel from the pipe 14 into the chamber, and an outwardly opening check valve 17 the passage of fuel from the chamber G into and through the pipe 15. The plunger or pump rod 18 (which is reciprocated through means to be hereinafter described) operates to pump to the atomizing or vaporizing cylinder through the pipe 15 a larger or smaller charge of fuel, according to the length of its stroke.

15 Bolted to the side of the main cylinder 5 is an auxiliary cylinder 19, the valve of which is provided at the outer side (away from the main cylinder) with a series of admission ports H communicating with a small fuel chamber I formed in a projection of the cylinder, into which fuel chamber the charges of fuel are delivered through the pipe 15 by the operation of the fuel pump. This fuel chamber also has un-

20 restricted communication with the steam dome 9 through the pipe 20. Opposite the ports H is a discharge port J communicating through the passage J' with an admission port K in the main cylinder opposite

25 the hot bulb or ignition chamber F. A check valve 21 which opens inwardly governs this port K.

The auxiliary piston 22 is operatively connected to the crank shaft 3 through the eccentric 23, eccentric ring 23', and eccentric rod 24, and the adjustment of the eccentric is such that the auxiliary piston will rise and fall simultaneously with the main piston 6. This auxiliary piston 22 is provided

30 with a discharge passage L leading from the upper side of the piston to a port adapted to register with the discharge port J in the cylinder wall when the piston is at or near its uppermost position. The clearance

35 chamber left at the limit of stroke of the piston is made very small, and to that end, in the present instance, and preferably, the top of the piston is formed with a conical recess (at the apex of which is the inner

40 end of the passage L), and the cylinder head with a corresponding conical projection.

45 The plunger 18 of the fuel pump is operated, and given a greater or less length of stroke, in the following manner: A lever 25, which at one end is pivoted to the base portion 1 of the engine and at its other end bears against a shifting or movable eccentric 26, rests intermediate its length upon the top of the plunger and operates to depress it as the

50 eccentric forces the lever downward. A coiled compression spring 27 surrounding the plunger and confined between the pump body and a disk secured to the top of the plunger by its reaction operates to lift the

55 rod as permitted to do so by the eccentric.

This eccentric is secured to or formed integrally with an arm 28 extending therefrom outside the plane of the eccentric, the outer end of the arm being pivotally mounted to a lug formed upon an arm of one of the fly wheels of the machine. Opposite the arm 28 is arranged a governor ball 29, also lying outside the plane of the eccentric. The bearing through the eccentric is somewhat elongated concentrically of the pivotal bearing 70 of the arm 28, and an adjustable spring 30 yieldingly tends to hold the eccentric in its position of greatest eccentricity. The eccentric is so timed as to cause a charge of fuel to be pumped into the fuel chamber I of the auxiliary cylinder shortly before the admission ports H of the auxiliary cylinder are uncovered by the auxiliary piston on its downward stroke, and the weight, arrangement and adjustment of the governor ball 75 and associated parts is such that when the speed of the engine rises above a predetermined point the centrifugal force of the governor ball will cause it to change its position so as to decrease the eccentricity of 80 the eccentric 26, whereby a shorter stroke is given to the lever 25 and the pump plunger 18, and less fuel is discharged into the fuel chamber I of the auxiliary cylinder. The speed of the engine, which under a given 85 load depends on the amount of fuel consumed, is thereby decreased. Inasmuch as the fuel chamber I is at all times under very little pressure, the action of the pump is not affected by variations of pressure in the 90 combustion chamber, and the pump responds regularly and uniformly to the action of the centrifugal governor.

The operation of the engine is as follows: Supposing the hot bulb or ignition chamber 95 F to be heated to the proper temperature, and assuming the main piston 6 to be on its downward stroke, the air in the crank chamber will be compressed until the piston uncovers the air inlet or intake port E when 100 the air under compression will enter and fill the combustion chamber B through such port, expelling the remaining products of combustion, a large part of which have already been vented through the exhaust 105 port D. At the same time the auxiliary piston 22 moves downward, producing exhaustion in the auxiliary cylinder until the admission ports H are uncovered. When this occurs the charge of fuel which has been 110 previously delivered into the small fuel chamber I is exposed to the action of the blast of hot steam drawn from the steam dome 9 through the pipe 20, and the hydro-carbon vapor thus formed fills the auxiliary 115 cylinder. As the two pistons now move upward the air in the main cylinder is compressed and at the end of the compression stroke occupies the portion B' of the combustion chamber. The hydro-carbon mix-

120

125

130

ture is simultaneously compressed until the discharge port J of the auxiliary cylinder registers with the port at the end of the discharge passage L of the auxiliary piston. 5 At this point the pressure of the hydrocarbon mixture is considerably higher than the pressure of the air in the portion B' of the main cylinder owing to the very small clearance in the auxiliary cylinder, and the 10 hydrocarbon vapor will therefore be rapidly discharged through the passage J' and around the check valve 21 through the admission port K, and become diffused with the air through the space B', when the heat 15 from the bulb 9 will instantly cause rapid and complete combustion of all the resultant mixture. The expansion of the products of combustion will now move the main piston 6 downward until the exhaust port D permits their escape, and the air inlet port E being immediately afterward uncovered, at the 20 end of the stroke of the main piston, another and similar series of operations takes place and is repeated so long as the engine continues to run.

The heat due to the intermittent combustion occurring in the combustion chamber is sufficient to maintain the hot bulb 9 at a proper temperature to perform its function 30 while the engine is continuously running, but it must be heated before the engine can be started, and the torch 12 is provided for this purpose.

While my invention has been illustrated 35 and described as embodied in a two-stroke cycle engine of particular form, it may with proper modification be applied to explosive engines of other types, and my claims are not intended to be restricted to the particular structure herein shown, or further 40 than is fairly required by the language in which they are stated.

I claim:

1. In an internal combustion engine having a combustion chamber and provided with a piston arranged to compress atmospheric air in such chamber, means for vaporizing charges of liquid fuel with a gaseous fluid and injecting the vaporized mixture into said chamber during compression therein comprising an auxiliary cylinder having an admission port and a discharge port communicating with the combustion chamber, a piston in said auxiliary cylinder governing said ports and uncovering said admission port at the end of an exhaust stroke and said discharge port at the end of a compression stroke, and means for supplying liquid fuel in the path of incoming gaseous fluid adjacent said admission port.
2. In an internal combustion engine having a combustion chamber and provided with a piston arranged to compress atmospheric air in such chamber, means for vaporizing charges of liquid fuel with steam and in-

jecting the vaporized mixture into said chamber during compression therein comprising an auxiliary cylinder having an admission port and a discharge port communicating with the combustion chamber, a piston in said auxiliary cylinder governing said ports and uncovering said admission port at the end of an exhaust stroke and said discharge port at the end of a compression stroke, a steam supply passage communicating with said admission port, and means for supplying liquid fuel in said passage adjacent said admission port.

3. In an internal combustion engine having a combustion chamber and provided with a piston arranged to compress atmospheric air in such chamber, means for vaporizing with steam charges of liquid fuel and injecting the same into said chamber during compression therein comprising an auxiliary cylinder having an admission port and a discharge port communicating with the combustion chamber, a piston in said auxiliary cylinder governing said ports and uncovering said admission port at the end of an exhaust stroke and said discharge port at the end of a compression stroke, a fuel chamber adjacent said admission port, a steam reservoir in communication with said fuel chamber, and means for delivering charges of liquid fuel into said fuel chamber.

4. In an internal combustion engine having a combustion chamber and provided with a piston arranged to compress atmospheric air in such chamber, the chamber having water jacket passages and a steam dome being arranged in communication with such passages, means for vaporizing with steam charges of liquid fuel and injecting the same into said chamber during compression therein comprising an auxiliary cylinder having an admission port communicating with said steam dome and a discharge port communicating with the combustion chamber, an auxiliary piston governing said ports and uncovering said admission port at the end of an exhaust stroke and said discharge port near the end of a compression stroke, a fuel chamber adjacent said admission port and in the path of communication with said steam dome, and means for delivering charges of liquid fuel into said fuel chamber.

5. In an internal combustion engine having a combustion chamber and provided with a piston arranged to compress atmospheric air in such chamber, means for vaporizing charges of liquid fuel with a gaseous fluid and injecting the same into said chamber comprising an auxiliary cylinder having an admission port and a discharge port, a passage connecting said discharge port and a port in the wall of said combustion chamber, a check valve adjacent said last mentioned port, a piston in said auxiliary cylinder governing said admission and discharge ports

- and uncovering the admission port at the end of an exhaust stroke and uncovering the discharge valve at the end of a compression stroke, a fuel chamber in the path of incoming gaseous fluid adjacent said admission valve, and a pump arranged to deliver charges of liquid fuel into said fuel chamber.
6. In an internal combustion engine having a combustion chamber and provided with a piston arranged to compress atmospheric air in such chamber, means for injecting charges of carbureted gaseous fluid into the compressed air in said chamber at the end of a compression stroke of said piston, comprising an auxiliary cylinder having an admission port and a discharge port communicating with said combustion chamber, an auxiliary piston governing said ports and uncovering said admission port near the end of an exhaust stroke and the discharge port near the end of a compression stroke, and means for delivering charges of fuel adjacent said admission port and in the path of incoming gaseous fluid.
7. An internal combustion engine comprising a closed crank and cylinder casing, a working piston dividing the interior thereof into a compression chamber and a combustion chamber, a valve arranged to admit atmospheric air into said compression chamber during exhaustion of pressure therein, a passage connecting said compression chamber with a port in the wall of the cylinder uncovered by the piston at the end of its out stroke, an exhaust port in the cylinder wall also uncovered by the piston at the end of its out stroke, an auxiliary cylinder having a fuel chamber and provided with an auxiliary piston for vaporizing the fuel with a gaseous fluid and injecting the vaporized mixture into said combustion chamber during compression therein, said auxiliary piston being arranged to move simultaneously with the working piston, a pump arranged to deliver a charge of fuel into said fuel chamber before an exhaust stroke of said auxiliary piston, said auxiliary cylinder being provided with an admission port adjacent said fuel chamber uncovered by the piston at the end of an exhaust stroke and with a discharge port uncovered at the end of a compression stroke which discharge port communicates with a passage of relatively small capacity in the cylinder walls terminating at a port in the combustion chamber of the engine, and a valve governing said last mentioned port.
8. An internal combustion engine comprising a crank shaft and crank, a crank and cylinder casing, a working piston connected with said crank dividing said casing into a compression chamber and a combustion chamber, said compression chamber having a self-opening air inlet valve and said com-

bustion chamber having an exhaust port and an air intake port communicating with said compression chamber, water-jacket passages in said cylinder casing, a steam dome communicating with said passages, an auxiliary cylinder having admission and discharge ports, a passage of relatively small capacity connecting said discharge port and the combustion chamber of the engine, an auxiliary piston operatively connected with said crank shaft to reciprocate synchronously with the working piston and governing said admission and discharge ports, said piston acting to vaporize fuel with steam and inject the vaporized fuel into the combustion chamber of the main cylinder during compression therein, a fuel chamber adjacent said admission port and in communication with said steam dome, and a pump having a reciprocating plunger and arranged to deliver charges of fuel to said fuel chamber, and operating connections intermediate said crank shaft and pump plunger for reciprocating the latter.

9. In an internal combustion engine, having a main cylinder including a combustion chamber and having means for compressing atmospheric air therein, an auxiliary cylinder having a fuel admission port and an auxiliary piston therein co-operatively arranged to intermittently vaporize charges of liquid fuel with a gaseous fluid and discharge the vaporized mixture into said combustion chamber at the period of compression of air therein, a fuel chamber in the path of incoming gaseous fluid adjacent said admission port, and a pump for delivering charges of fuel to said fuel chamber.

10. In an internal combustion engine having a main cylinder including a combustion chamber, and having means for compressing atmospheric air therein, an auxiliary cylinder having a plurality of small admission ports and provided with an auxiliary piston co-operatively arranged to intermittently vaporize charges of liquid fuel with a gaseous fluid and discharge the vaporized mixture into said combustion chamber at the period of compression of air therein, a fuel chamber in the path of incoming gaseous fluid adjacent said admission port, and a pump for delivering charges of fuel to said fuel chamber.

11. In an internal combustion engine having a main cylinder including a combustion chamber and having means for compressing atmospheric air therein, an auxiliary cylinder having a fuel admission port and an auxiliary piston therein co-operatively arranged to intermittently vaporize with steam charges of liquid fluid and discharge the same into said combustion chamber at the period of compression of air therein, a fuel chamber adjacent said admission port, a steam reservoir in communication with said

fuel chamber, and a pump for delivering charges of fuel to said fuel chamber.

12. In an internal combustion engine having a main cylinder including a water-jacketed combustion chamber and a steam dome communicating with the water jacket passages and having means for compressing atmospheric air in said combustion chamber, an auxiliary cylinder having a fuel admission port and arranged to intermittently vaporize with steam charges of liquid fuel and discharge the same into said combustion chamber at the period of compression of air therein, a fuel chamber adjacent said admission port and in communication with said steam dome, and a pump for delivering charges of fuel to said fuel chamber.
13. In an internal combustion engine having a main cylinder including a combustion chamber and having means for compressing atmospheric air therein, an auxiliary cylinder having a fuel admission port and arranged to intermittently vaporize charges of liquid fuel with a gaseous fluid and discharge the vaporized mixture into said combustion chamber at the period of compression of air therein, a fuel chamber in the path of incoming gaseous fluid adjacent said admission port, and a pump for delivering charges of fuel to said fuel chamber, said pump having a governor-controlled variable stroke.

14. An internal combustion engine comprising a combustion chamber provided with a piston arranged to compress atmospheric air in such chamber, and means for injecting vaporized charges of fuel and steam into said chamber comprising an auxiliary cylinder, a fuel supply passage communicating with said cylinder, a steam passage also communicating therewith, and a piston in said cylinder arranged to draw steam and fuel into the cylinder at an exhaust stroke, and to expel the vaporized mixture at a compression stroke into compressed air in the combustion chamber of the engine.

15. An internal combustion engine comprising a combustion chamber provided with a piston arranged to compress atmospheric air in such chamber, and means for injecting vaporized charges of fuel and steam into said chamber comprising an auxiliary cylinder having admission and discharge ports, a steam supply passage communicating with said admission port, a fuel supply passage terminating in said steam passage adjacent said admission port, and

an auxiliary piston in said cylinder arranged to uncover said admission port at 60 the end of an exhaust stroke to draw steam and fuel into the cylinder at a high velocity and vaporize the same and to uncover the discharge port at the end of a compression stroke to force the resultant mixture into 65 the compressed air in the combustion chamber.

16. In an internal combustion engine having a main cylinder and a piston therein, means for vaporizing charges of liquid fuel 70 with a gaseous fluid and injecting the vaporized mixture into said main cylinder comprising an auxiliary cylinder having an admission port and also having a discharge port communicating with the main 75 cylinder, said cylinder being otherwise imperforate, an auxiliary piston in said auxiliary cylinder governing said ports and uncovering said admission port at the end of an exhaust stroke to vaporize the fuel and 80 said discharge port at the end of a compression stroke to inject the vaporized mixture with the main cylinder, and means for supplying liquid fuel and the gas for vaporizing the same adjacent said admission port. 85

17. In an explosive engine, a cylinder forming a combustion chamber, a piston arranged to compress atmospheric air therein, and means for vaporizing a charge of fuel with a charge of steam and injecting 90 the vaporized charge of mixed steam and fuel into the compressed air in said cylinder at the end of a compression stroke of said piston.

18. In an explosive engine, a cylinder 95 forming a combustion chamber, means for intermittently charging said cylinder with air, and an auxiliary cylinder and piston arranged to intermittently vaporize a charge of liquid fuel with steam and inject 100 the carbureted steam into the charge of air in the combustion chamber of the engine.

19. In an explosive engine, a cylinder forming a combustion chamber, means for intermittently compressing a charge of air 105 in said cylinder, an auxiliary cylinder and an auxiliary piston in said cylinder arranged to alternately vaporize a charge of liquid fuel with a gaseous fluid and then compress the carbureted vapor to a preponderant 110 pressure and inject it into the compressed charge of air in the combustion chamber.
